(57) CLAIM

The ornamental design for a display screen with graphical user interface, as shown and described.

DESCRIPTION

FIG. 1 is a front view of a 1st embodiment of display screen with graphical user interface according to my design;
 FIG. 2 is a front view of a 2nd embodiment of display screen with graphical user interface according to my design;
 FIG. 3 is a front view of a 3rd embodiment of display screen with graphical user interface according to my design;
 FIG. 4 is a front view of a 4th embodiment of display screen with graphical user interface according to my design;
 FIG. 5 is a front view of a 5th embodiment of display screen with graphical user interface according to my design;
 FIG. 6 is a front view of a 6th embodiment of display screen with graphical user interface according to my design;
 FIG. 7 is a front view of a 7th embodiment of display screen with graphical user interface according to my design;
 FIG. 8 is a front view of an 8th embodiment of display screen with graphical user interface according to my design;
 FIG. 9 is a front view of a 9th embodiment of display screen with graphical user interface according to my design; and
 FIG. 10 is a front view of a 10th embodiment of display screen with graphical user interface according to my design;
 FIG. 11 is a front view of an 11th embodiment of display screen with graphical user interface according to my design;
 FIG. 12 is a front view of a 12th embodiment of display screen with graphical user interface according to my design;
 FIG. 13 is a front view of a 13th embodiment of display screen with graphical user interface according to my design;
 FIG. 14 is a front view of a 14th embodiment of display screen with graphical user interface according to my design;
 FIG. 15 is a front view of a 15th embodiment of display screen with graphical user interface according to my design;
 FIG. 16 is a front view of a 16th embodiment of display screen with graphical user interface according to my design;
 FIG. 17 is a front view of a 17th embodiment of display screen with graphical user interface according to my design;
 FIG. 18 is a front view of an 18th embodiment of display screen with graphical user interface according to my design;
 FIG. 19 is a front view of a 19th embodiment of display screen with graphical user interface according to my design;
 FIG. 20 is a front view of a 20th embodiment of display screen with graphical user interface according to my design;
